Primary Examiner — Marianne Pandozzi(74) *Attorney, Agent, or Firm* — Seth M. Blum(57) **CLAIM**

The ornamental design for a container support structure, as shown and described.

DESCRIPTION

FIG. 1 is a front perspective view of a container support structure showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken lines depict portions of the container support structure that forms no part of the claimed design.
